(57) **CLAIM**

The ornamental design for a watch head, as shown and
described.

DESCRIPTION

FIG. 1 is a top plan view of a watch head showing our new
design;

FIG. 2 is a bottom plan view;

FIG. 3 is a right side elevational view thereof, the left side
being mirror image; and,

FIG. 4 is a first end elevational view thereof, the second end
being mirror image.

The broken-line showings are environmental only and form
no part of the claimed design.
